SUPPORT FOR CLOTHESLINES

Robert M. Healy, Flushing, N. Y.

Application December 9, 1941, Serial No. 422,212

5 Claims. (Cl. 211—119.07)

This invention relates to a device for supporting a pulley clothes-line and particularly to an adjustable support which enables the user to hang the clothes on the line without leaning through a window or other opening.

Pulley clothes-lines are commonly used and are generally supported by a pulley attached to a window-casing and another pulley on some distant support. In hanging clothes on such a line, the user stands inside and leans through the window opening. The arrangement is inconvenient. Moreover, numerous serious and often fatal accidents have occurred where the person using the line has fallen through the window opening in attempting to reach the line.

It is the object of the present invention to provide a safe and convenient support for a clothes-line which enables the user to hang clothes on the line inside the window and thereafter adjust the support so that the window may be closed.

Another object of the invention is the provision of a clothes-line support which, when adjusted to permit closing of the window, will hold the line sufficiently taut.

Other objects and advantages of the invention will be apparent as it is better understood by reference to the following specification and the accompanying drawing, in which

Fig. 1 is a view in perspective illustrating the application of a device constructed in accordance with the invention;

Fig. 2 is a similar view illustrating the position of the pulley-supporting arm inside the window;

Fig. 3 is an elevation of the device;

Fig. 4 is a plan view thereof, showing the pulley-supporting arm inside the window;

Fig. 5 is a view similar to Fig. 4, showing the arm outside the window;

Fig. 6 is an elevation showing the bar in raised position; and

Fig. 7 is a vertical section of a portion of the device illustrating the details thereof.

The invention depends upon the use of a swinging arm supported in a suitable bracket which may be secured to the window casing or other available part of the building to which the device is attached. The swinging arm carries a pulley which supports the clothes-line and is adapted to be adjusted to positions either outside or inside the window casing by a simple swinging movement. To avoid slackening of the line when the arm is disposed in its normal position outside of the window, an adjustable bar is provided to engage the clothes-line and to hold it

taut. The adjustable arm is provided with a latch which enables the user to lock it in the desired position. Preferably the arm is designed so that when it is inside the window it extends at a slight angle to a perpendicular position with respect to the wall, so that the line will run freely and the clothes may be readily hung thereon.

Referring to Fig. 7 of the drawing, 5 indicates a bracket of any suitable material, preferably metal, which may be secured by screws 6 or other convenient fastening means to a window casing 7 supported in a wall 8 as shown in Figs. 1 and 2. The end of the bracket 5 is bifurcated and provided with two cylindrical supports 9 adapted to receive a cylindrical sleeve 10 which may be secured in any convenient way, as for example by upsetting the ends of the sleeve.

An arm 11 carrying a pulley 12 at its end is provided at its opposite end with a cylindrical eye 13 adapted to embrace the sleeve 10, whereby the arm 11 is supported for pivotal movement. A plate 14 likewise surrounds the sleeve 10 and is provided with a notch 15 which engages the bracket 5 so that the plate is held in fixed position. The plate 14 is provided also with an opening 16 and a plurality of notches 17 and with a shoulder 18. A sliding latch 19 is supported in the stirrup 20 fastened to the arm 11 and is adapted to engage the shoulder 18 or one of the notches 17 to hold the arm 11 in adjusted position.

A cylindrical bar 21 is slidably supported in the sleeve 10. At the upper end of the bar 21, a nut 22 or other convenient means for affording an abutment prevents the bar from escaping from the sleeve. At its lower end the bar 21 is provided with an adjustable hook 23 which is adapted to be disposed in the opening 16 provided in the plate 14 when the bar is lifted to the position indicated in Fig. 6. As indicated in Fig. 4, the arm 11 is preferably formed with an angle 24 so that when it is adjusted to position inside the window the end carrying the pulley 12 will be positioned so that the clothes-line 25 will run freely without interfering with the bar 21. Obviously some other formation may be employed to accomplish this purpose.

In using the device, the bracket 5 is secured to the window casing or other support as indicated in Figs. 1 and 2 and the line 25 is disposed about the pulley 12 and another suitable pulley 26 which may be fastened to any convenient support. The normal position of the arm 11 is indicated in Fig. 1, the clothes-line 25 being disposed about the bar 21 which is in its lowered position.

The arm may be held by engagement of the latch 19 with one of the notches 17. When clothes are to be fastened on or removed from the line 25, the latch 19 is released and the arm 11 is swung inwardly through the window casing. The bar 21 is then raised and secured by means of the hook 23 so that the line is free. The person using the line may stand within the window and either add clothes to or remove them from the line without leaning through the window casing. When the operation is completed, the line is pushed towards the window casing, either manually or by swinging the bar 11 clockwise, after which the bar 21 is released and dropped in front of the line into the position shown in Fig. 1, so that the line 25 will pass about it when the arm 11 is swung through the window opening. While the arm 11 is in its inner position it may be held by engagement of the latch 19 with the shoulder 18 and the latch must be released before the arm 11 is moved to its normal position outside the window. In either its inner or outer position the arm 11 is held securely. The line 25 will run freely while the arm 11 is in its inner position. When the arm 11 is moved outwardly through the window to its normal position, the line remains on the pulley 12 and slackening is avoided by its engagement with the bar 21.

The device is easily manipulated and affords absolute safety for the user because all of the steps necessary to manipulate the device and to use the clothes-line may be carried out without leaning through the window opening.

Various changes may be made in the details of arrangement and construction of the device without departing from the invention or sacrificing any of the advantages thereof.

I claim:

1. A safety support for pulley clothes-lines comprising a bracket, an arm pivotally supported thereon, a pulley at the free end of the arm, a bar vertically movable to and from line-engaging position affording line-engaging means supported on the bracket concentrically with the pivotal support of the arm, and means for locking the arm in adjusted position.

2. A safety support for pulley clothes-lines comprising a bracket, an arm pivotally supported thereon, a pulley mounted thereon, the arm being formed so that the pulley is offset from a line perpendicular to the bracket at the point of support of the arm, and line-engaging means supported on the bracket concentrically with the pivotal support of the arm and vertically movable to and from line-engaging position.

3. A safety support for pulley clothes-lines comprising a bracket, an arm pivotally supported thereon, means for locking the arm in adjusted position, a pulley mounted on the arm, the arm being formed so that the pulley is off-set from a line perpendicular to the bracket at the point of support of the arm, and line-engaging means supported on the bracket concentrically with the pivotal support of the arm and vertically movable to and from line-engaging position.

4. A safety support for pulley clothes-lines comprising a bracket, an arm pivotally supported thereon, means for locking the arm in selectively adjusted positions, a pulley mounted on the arm, the arm being formed so that the pulley is offset from a line perpendicular to the bracket at the point of support of the arm, and line-engaging means supported on the bracket concentrically with the pivotal support of the arm and vertically movable to and from line-engaging position.

5. A safety support for pulley clothes-lines comprising a bracket adapted to be mounted adjacent a window or the like, an arm pivotally supported on said bracket to swing in a substantially horizontal plane to a position inside the window or outside thereof, a pulley mounted on the arm about which the clothesline passes, and means for taking up slack in the clothes-line comprising a member supported on the bracket coaxially with the pivotal support for the arm and movable axially from an inoperative position to an operative position in which both reaches of the clothes-line may be moved to a position to pass around said member when the arm is swung from a position inside the window to a position outside the window.
